ELBERT L. HYDE, OF SHAKER HEIGHTS, OHIO

EXERCISING MACHINE

Application filed February 25, 1928. Serial No. 257,016.

This invention relates to exercising machines of that type which employs an applicator by which vibrations are imparted to the body, the applicator usually being a flexible strap or band, one or both ends of which are attached to a suitable operating device, such as a knob or stud rotated or otherwise moved to produce back and forth endwise movement of the applicator.

10 The object of the present invention is to provide an improved vibrating or exercising machine including such an operating knob or stud whose amplitude of vibration may be varied within any reasonable or desired limits according to the pull of the operator upon the applicator and in which, moreover, the parts may be so arranged that the operating device for the applicator so long as there is no pull upon it, is at rest, or practically so, 20 when the machine is running.

Further objects of the invention are in part obvious and in part will appear more in detail hereinafter.

In the drawings, Fig. 1 is a front elevation 25 of one form of machine embodying the invention; Fig. 2 is an end view, partly broken out and in section, of one end head; Fig. 3 is a detail sectional view on the line 3—3, Figs. 1 and 2; and Fig. 4 is a detail view of one end 30 of an applicator.

The main elements of the machine require no detailed description, as they are well known. Fig. 1 shows a shaft 1 rotatable in frame bearings 2 and provided at its opposite ends with heads 3, each one of which supports an operating device for an applicator, such as the headed wrist pin stud 4 having an annular groove 5 to receive the applicator. The bearings 2 may be mounted in any suitable frame or base resting on the floor or a table or fastened to a wall or any other suitable fixed support. Shaft 1 may be rotated in any suitable manner and is shown as provided with a belt pulley 6 for receiving a belt driven by any suitable device, such as an electric motor (not shown). The applicator may include a canvas or other flexible band or strap 7 with its end portions suitably stiffened, such as by being provided 45 with a fairly thick leather end portion 8 pro-

vided with a buttonhole slot including a large opening 9 adapted to be slipped over the head 10 of the stud 4 and connected by a reduced portion 11 to a smaller opening 12, this arrangement permitting the applicator to be 55 slipped on to the stud and its leather end to ride in the annular groove 5.

The two heads 3, as to their internal mechanism and operating devices, are alike, so that the description of one will suffice for 60 both. These heads are shown in Figs. 2 and 3.

Each head comprises a relatively thick disc-like body portion 15 provided with a tubular boss 16 fitted over the driving shaft 1 and suitably secured to rotate therewith, as by the cross pin 17. The back of each body is hollowed out or recessed, as at 18, to reduce weight, providing an annular flange 19 with a smooth peripheral surface and also a relatively large reinforcing cross rib 20 through 65 which extends a cylindrical chamber or opening 21, which may be bored or drilled. In said opening slides a carrier 22 having a tubular body portion, an inner chamber 23 and a laterally extending post including a square 70 base 24 and a threaded outer end 25 on which the stud 4 is screwed. This carrier has its outer end closed, either by an integral end wall or by the plug or disc 26 adjustable endwise in the chamber 23 along the screw 75 threads 27 for a purpose which will appear. The tube wall at the other end of the body has its inner surface slightly tapered, as at 28. This carrier may be made in several ways, either as a piece of seamless tubing to which 80 the lateral post is welded, or it may be formed of a casting suitably machined, as by a turning operation, to form its end portions and slightly reduced, as at 29, in the zone of the lateral stud. This body is a close sliding fit 85 in the cylindrical chamber or opening 21 and serves as a piston to compress the air between its closed outer end and a closure at the outer end of the chamber 21, such as a plug or cap 30 threaded into the opening and provided with a through port 31, one end of which forms a seat for a ball valve 32. The inner 90 surface of the plug 30 is tapered toward said seat, as at 33.

Within the chamber 23 of the carrier nests 100

a spiral compression spring 34 guided by the tapered portion 28 and surrounding a guiding pilot 35 suitably attached to a closure plate 36 at the opposite end of the through opening 21. 5 This closure not only closes one end of the chamber 21 but also closes the end of a slot 37 in the outer face of the head 3, and between the walls of which slot the square base 24 of the carrier post slides.

10 The threaded portion 25 of said post is a little shorter than the opening in the stud 4 into which it screws, and the shoulder 38 at the inner end of said threads lies very slightly outwardly beyond the face of the head 3, (as shown slightly exaggerated in Fig. 3) so that when the stud is screwed home to said shoulder its inner surface does not actually contact with the outer face of the head. Moreover, the threads 25 on one stud will be right handed and on the other stud left handed, so that when the machine is running the friction effect of the applicator ends on the studs will always tend to screw them fast at both ends of the operating shaft.

15 25 It will be observed from Fig. 2 that the inner end of slot 37 forms a stop limiting the movement of the carrier 22 caused by expansion of the compression spring 34, which is under some compression in that view. In such position the axis of stud 4 coincides with the axis of the operating shaft 1. Therefore, with the parts in the position shown, the stud 4 spins on its own axis when shaft 1 is rotated. That is true, even though the applicator ends 30 are fastened to the two studs 4. As a consequence, there is no eccentrically rotating part when the machine is running and the applicator strap hangs loosely and at rest from the studs when it is not applied to the body. If the machine is inadvertently left running there is no tendency for the applicator to coil itself about rotating parts, nor is there any danger of being injured by accidentally touching a rapidly rotating eccentric part, because there are none. However, assuming 35 both ends of a double ended applicator secured to the two studs and looped around the body of an operator, if the operator applies a pull to the applicator, as by leaning back in its loop, the pull is applied more or less equally to the studs 4. The two heads 3 are secured to their respective ends of shaft 1 in reversed position or angularly displaced 180° to each other, as shown in Fig. 1. Shaft 1 rotates at approximately 300 R. P. M. Nevertheless, during each complete rotation a pull on one applicator end is applied to its stud 4 in all radial directions around the stud axis. While the pull has its effect in all radial positions, for simple explanation we can refer 40 only to the diametrically opposite pulls lengthwise of the line of the movement of piston 22. In one direction of pull the tendency is to compress the spring 34 and move stud 4 outwardly and in the opposite direction of

pull the tendency is to assist the expansion of the spring in returning the piston 22. In practice, it is found that this pull applied to the applicator end tends to move the stud 4 outwardly to a position eccentric to the axis 70 of shaft 1, and cause it to rotate around said axis, thereby applying vibration or back and forth pull to the applicator end.

Practice and experience show that if the ball valve 32 is omitted, so that the piston chamber 21 has free relief to the atmosphere, the applicator pull produces eccentricity of the stud 4 through the major part of the rotation of the head, with a quick inward movement of the piston and stud 4 when the direction of applicator pull is in the direction of expansion of spring 34, producing a motion of crank 4 around the shaft axis which is not a true circle but more or less heart-shaped, with a short inward lobe at 85 the top of the heart. For this reason the device is provided with means for cushioning or retarding return of the piston by the spring 34 after it has been moved to carry the stud 4 out to an eccentric position. The means shown includes the ball valve 32. When the device begins to rotate centrifugal force carries the ball 32 outwardly and along the tapered seat 33 to the position shown in Fig. 2, closing the port 31 against outward flow of air, but permitting air to rapidly flow inwardly as the piston moves away from the port 31.

90 The net effect of a pull on the applicator is to move the stud 4 outwardly to an eccentric position, depending upon the compressive force of the spring 34 and the pull on the applicator. The strength of the spring initially chosen may be of a desired value or may be adjusted by shims or washers or by adjusting the plug 26. In the extreme outward position of piston 22 its end abuts the closure and stop plate 36. As the pull on the applicator is reduced spring 34 expands and the air in chamber 21 is vented 100 to the atmosphere, either around the piston (which is not an absolutely tight fit in the chamber) or through an adjustable relief port or valve provided for the purpose, such as the needle valve 41 having a valve head 105 cooperating with a valve seat at the outer end of a small relief port 42 communicating with a large passage 43 to atmosphere. This valve may be adjusted in matched relation 115 according to the tightness of fit of the piston in the cylinder, so that return movement of the piston from its extreme outward position to the position shown in Fig. 2 takes one or two seconds. Of course, slackening up on the 120 applicator pull permits the piston to return toward its initial position, so that the device is more or less self-governing and maintains the stud 4 at a definite eccentric position 125 depending upon the applicator pull.

130 In operation the device responds by more

or less of a pumping operation. In other words, an endwise pull on the applicator throws the piston outwardly and in the opposite direction of pull, 1/600 of a minute later, the piston tends to snap back to central position, but in so doing it compresses the air in chamber 21. If the relief port is sufficiently restricted the device will therefore pump up pressure in chamber 21 at a greater rate than the vent port can relieve it, so that a cushion is provided and maintained to retard return piston movement.

The device may be readily accommodated to persons of varying strength, such as a frail woman and a heavy man. This can be accomplished either by inserting light or heavy springs 34, by shims or washers, or by adjustment of the plug 26. The lighter spring is used for a heavy or strong man, because it is desirable to permit him to more readily move the piston 22 to its extreme outward position, while in the case of a frail woman, the spring should be more powerful to prevent her from moving the stud 4 outwardly too far. In this way it is possible to limit the amplitude of the vibration received by a given person to an amount adjusted to his or her own strength and vigor.

Ordinarily, the device requires no lubrication, although it may be lubricated if desired. In that case the piston is a more tight fit or seal in its chamber and it is necessary to provide suitable means for trapping the oil or lubricant and prevent it from being thrown outwardly through the port 31, which should therefore be directed laterally and trap the oil within the flange 19 of the head. It will be noticed that the piston 22 has a long bearing in its chamber and that the square base 24 is a close sliding fit in the slot 37, so that the square base 24 of the post supporting the driving stud is firmly supported in all positions of the carrier piston.

Obviously, it is unnecessary to use both operating heads at the same time. While the applicator is frequently used by applying its two ends to the oppositely moving studs and applying the body to its loop, nevertheless the applicator may be single ended and applied only to one operating stud, and may have a single handle, so that by pulling on it with one hand or wrapping it around the body and pulling on its free end, the vibration of one stud is effective.

What I claim is:

1. An exercising machine, comprising an operating device adapted to have an applicator attached thereto, means for producing vibrations of said operating device, and yieldable means having a normal tendency to reduce the amplitude of said vibrations, said yielding means being connected to the operating device in such manner that the force applied by the operator to the applicator and thereby exerted on the operating device

causes said means to yield and thereby increase the amplitude of said vibrations.

2. An exercising machine, comprising a driving shaft, two operating devices vibrated in opposition to each other by said shaft and each adapted to have an applicator end attached thereto, and yieldable means for said operating devices and having a normal tendency to reduce the amplitude of the vibrations thereof, said yieldable means being connected to said operating devices in such manner that the force applied by the operator to either applicator end causes said yielding means to yield and thereby increase the amplitude of said vibrations.

3. An exercising machine, comprising a rotating shaft, wrist pin members operated thereby and mounted for movement toward and from the shaft axis, each wrist pin member being adapted to receive an applicator end, and yieldable means effective upon each wrist pin member and normally tending to move it toward the shaft axis, whereby a pull by the operator upon an applicator end exerts the contrary effect upon its wrist pin member and moves it away from the axis to increase its throw and the amplitude of vibrations thereby produced.

4. An exercising machine, comprising a shaft, an operating wrist pin movably mounted upon said shaft and provided with means whereby an applicator end may be connected thereto, yielding means normally tending to move said wrist pin toward the shaft center to reduce eccentric travel thereof around the shaft axis, and means for retarding such movement.

5. An exercising machine, comprising a driving shaft provided with two heads, an operating device transversely movable on each head toward and from central position and provided with means whereby an applicator end may be connected thereto, yielding means for moving each device inwardly, and means for adjusting said yielding means.

6. In an exercising machine, a vibrator device adapted for connection to a rotating driver, said device including a member mounted for movement toward and from the axis of rotation and arranged for operative connection of an applicator thereto, means whereby said member tends to move toward said axis when the driver is rotating, and means sensitive to outward movement of said device for retarding its recession.

7. In an exercising machine, a vibrator device adapted for connection to a rotating driver, said device including a member mounted for movement toward and from the axis of rotation and arranged for operative connection of an applicator thereto, means whereby said member tends to move toward said axis when the driver is rotating, a piston connected to said member, and a cylinder for said piston.

8. In an exercising machine, a vibrator device adapted for connection to a rotating driver, said device including a member mounted for movement toward and from the axis of rotation and arranged for operative connection of an applicator thereto, means whereby said member tends to move toward said axis when the driver is rotating, a piston connected to said member, a cylinder for said piston, and valve mechanism therefor.
9. In an exercising machine, a vibrator device adapted for connection to a rotating driver, said device including a member mounted for movement toward and from the axis of rotation and arranged for operative connection of an applicator thereto, means whereby said member tends to move toward said axis when the driver is rotating, a piston connected to said member, and a cylinder for said piston, and valve mechanism therefor including a ball valve seated by centrifugal force when said device rotates.
10. An exercising machine, comprising an operating device adapted to have an applicator connected thereto, means for producing vibrations of said operating device, said operating device being adjustable in two directions to either increase or diminish the amplitude of its vibrations, and yieldable means having a normal tendency to adjust the operating device in one of said directions, whereby a force applied by the operator to the applicator causes said means to yield and produce motion of the operating device in the other direction.
11. An exercising machine, comprising an operating device adapted to have an applicator attached thereto, means for producing vibrations of said device, and means whereby during the production of such vibrations their amplitude is yieldingly reduced in opposition to the force applied by the operator to the applicator and the amplitude of vibrations under any given condition is therefore automatically varied in accordance with such force.

In testimony whereof I hereby affix my signature.
